UNITED STATES PATENT OFFICE.

LOUISA CASEMERE, OF WARREN, PENNSYLVANIA.

DESIGN FOR A GAS-BURNER FRAME.

SPECIFICATION forming part of Design No. 22,781, dated September 12, 1893.

Application filed August 21, 1893. Serial No. 483,684. Term of patent 14 years.

To all whom it may concern:

Be it known that I, LOUISA CASEMERE, a citizen of the United States, residing at Warren, in the county of Warren and State of Pennsylvania, have invented and produced a new and original Design for Gas-Burner Frames, of which the following is a specification.

This design has for its object to provide a novel and ornamental gas burner frame which presents a distinguishing and characteristic appearance to the eye.

The design consists essentially in an oblong body having a flattened bottom wall, rounded vertical end walls, rectilinear vertical side walls, and a flat top wall, from the center of which rises a vertical stem surmounted by an oblong plate, the lower side of which is centrally swelled and inclines upwardly toward opposite ends thereof.

The design is illustrated by the accompanying drawings, in which the figure is a perspective view of the gas burner frame.

In the drawing illustrating the design the

numeral 1 indicates the flattened bottom wall of the body; 2 the rounded vertical end walls; 25 3 the rectilinear vertical side walls; and 4 the flat top wall.

The central portion of the flat top wall is provided with a circular vertical projection 5, decreasing in diameter from its lower to its 30 upper portion, and from the center of this circular projection rises a vertical stem 6 surmounted by the oblong plate 7, the lower side of which is centrally swelled, as at 8, and inclines upwardly, as at 9 toward the opposite 35 rounded ends 10 of the plate.

What I claim is—

The design for a gas burner frame, substantially as shown and described.

In testimony whereof I have hereunto set 40 my hand in presence of two subscribing witnesses.

LOUISA CASEMERE.
